UNITED STATES PATENT OFFICE

127,122

DESIGN FOR A BREAD CONTAINER

Manuel S. Ziskin, University Heights, Ohio, assignor to Kromex Corporation, Cleveland, Ohio, a corporation of Ohio

Application March 12, 1941, Serial No. 99,530

Term of patent 7 years

To all whom it may concern:

Be it known that I, Manuel S. Ziskin, a citizen of the United States and a resident of University Heights, county of Cuyahoga, and State of Ohio, have invented a new, original, and ornamental Design for a Bread Container, of which the following is a specification, reference being had to the accompanying drawing, forming a part hereof.

In said annexed drawing:

Fig. 1 is a top plan view of the bread container, showing my design;

Fig. 2 is a side elevational view; and

Fig. 3 is an end elevational view thereof.

Fig. 4 is an enlarged fragmentary sectional view, taken on the line 4—4 of Fig. 1 and in the direction of the arrows.

I claim:

The ornamental design for a bread container, as shown.

MANUEL S. ZISKIN.
